DEVICE FOR CLOSING RECTANGULAR BAG
ENDSGustaf Örström, Alsten, Sweden, assignor to
Aktiebolaget Gerh. Arehns Mekaniska Verk-
stad, Stockholm, SwedenApplication August 29, 1936, Serial No. 98,589
In Sweden August 31, 1935

15 Claims. (Cl. 93—6)

This invention relates to improvements in devices for closing rectangular bag ends and it is an object of my invention to secure in a simple manner formation of distinct fold lines in the bag ends, so as to considerably facilitate subsequent closing, e. g. by the coiling of the bag end.

A further object of my invention is to provide means for forming distinct fold lines by collapsing the bag end without causing any undesired 10 folds, particularly with the view of facilitating subsequent closing of the flattened end by coiling same.

In the drawings:

Fig. 1 is a side view of part of a machine comprising the device according to the invention;

Fig. 2 is a plan view of the device;

Fig. 3 is a front elevational view of part of a machine comprising the device;

Fig. 4 is a vertical section of part of the device;

Fig. 5 is a vertical section taken at a right angle to the section shown in Fig. 4;

Fig. 6 is a diagrammatic plan view of the parts shown in Figs. 4 and 5; and

Fig. 7 shows the parts illustrated in Fig. 5 in downfolded positions.

Referring to the drawings, a conveyor 1 is arranged successively to carry filled bags A in the direction of the arrow (Fig. 3) into a position 30 upon a lifting piston 2 which has for its purpose to elevate the bags through a funnel-shaped guide 3, narrowed at its top, to the operating position shown in Figs. 4 and 5, whereby the bag is somewhat lessened in cross-section at its upper 35 end. The lifting piston 2 is raised and lowered by an arm 6 pivotally journaled on a pin 4 in the machine frame 5. The arm 6 is actuated by a cam disc 7, which is secured to the driving shaft 8. The closing mechanism is fixed to four standards 9 and contains two oppositely disposed triangular flaps 10 for tucking in a pair of opposite sides of the bag, and flaps 11 and 12 for folding the two remaining sides of the bag. The pivotal axes of all the flaps extend at the upper edges of the guide 3. The flaps 10 are fixed to shaft pins 13, journaled in a frame 14, to the outer ends of which pins 13 are secured arms 15, which are each pivotally connected to a link rod 16. The link rods 16 are pivotally connected to a yoke 17 secured to two vertical spindles 18, which are slidably arranged in the frame 14. To the spindles 18 are connected pivotally by means of forks two arms 19, which are secured to a shaft 20 rotatably journaled in the frame 14. One of the arms 19 is provided with a rearwardly directed

arm 21, to which is pivotally connected a rod 22, the length of which can be adjusted. The rod 22 is given an up and down motion by means of a cam disc 23 secured to a rotatably journaled shaft 24.

The up and down movement of the yoke 17 is transmitted also to the flaps 11 and 12. The latter are fixed to pins 25, to which, in addition, are secured arms 26, which are each connected pivotally to a link rod 27 and 28. The link rod 10 21, which transmits the movements of the flap 11, is connected pivotally at its upper end to one of the two arms 29, which project laterally from the yoke 17. The link rod 28, which transmits the movements of the yoke 17 to the flap 12, is 15 provided at its upper end with an oblong hole or slot 30, embracing the other arm 29, and the one of the arms 26, that is connected to the lid 12, is turned downwards by a spring 31, connected to the machine frame 5, so that the arm 29 rests 20 against the upper edge of the hole 30.

The shaft 8 drives the shaft 24 by means of a gearing 33, 34 whereby the spindles 18 are moved up and down in a timed relation to the movements of the piston 2 in such manner that the flaps 10, 11 and 12 are maintained in the raised position while the piston moves upwardly, thereafter, when the piston is in its uppermost position, folded together and raised again, whereafter the piston is moved downwards.

The operation of the device is the following: The upward movement of the lifting piston 2 is adjusted so that it is arrested when the filling material and the lowest part of the bag at which creases may be formed are at a level with the upper edge of the guide 3. The yoke 17 is then moved downwardly and by convenient adjustment of the arms 15 on the pins 13 the flaps 10 are first swung in against the bag, whereby they are folded down and tuck in two opposite sides of the bag end, so that they become chute-shaped, as shown in Fig. 6. The flap 12 immediately follows the flaps 10 and folds in a third side onto the flaps 10, and the flap 11 follows somewhat after the flap 12 and folds in the fourth side of the bag simultaneously collapsing and folding down the bag end onto the opposite folding flap 12, as shown in Fig. 7. During this final folding step the flap 12 is kept in a downfolded position by spring force, for one arm 29 moves freely downwards in the slot 30 in the link rod 28. After thus having finished the folding the flaps 10, 11 and 12 are again swung up into the positions shown in Figs. 4 and 5, whereafter the piston 2 is moved down, so that the bag rests on 50 55 60 65 the conveyor 1, which transports it further in the direction of the arrow (Fig. 3), conveniently beneath a guide plate which folds the bag end again, which on the downward movement out of the guide 3 has been erected. Thereafter the bag 5 is conveniently advanced to a coiling device which rolls up the flattened and downfolded bag end on forming a transverse fold the position of which is determined by the sharp fold which is obtained on folding down the bag end over the front edge 10 32 of the flap 12. The direction of the coiling should be the reverse of the preceding folding down of the bag end.

What I claim is:

15 1. In a device for closing rectangular bag ends, two pivotally journalled, substantially flat and oppositely disposed members for tucking in the ends of two opposite walls of a bag, two pivotally journalled, substantially flat and oppositely disposed members for folding the ends of the two 20 remaining bag walls, driving means for folding down said tucking members towards each other in advance of said folding members and folding down said folding members towards each other 25 upon said tucking members, an elevator member, and a mechanism operatively connected to said driving means to move said elevator member to introduce the bag end between said tucking and folding members immediately before they are 30 folded down.

2. In a device for closing rectangular bag ends, two pivotally journalled, oppositely disposed members for tucking in the ends of two opposite walls of a bag, two pivotally journalled, oppositely disposed members for folding the ends of the two remaining bag walls, driving means for folding down said tucking members towards each other in advance of said folding members and folding down said folding members towards each 40 other upon said tucking members, a member for supporting said bag, and a mechanism operatively connected to said driving means to move said tucking, folding and supporting members relative to each other to embrace the bag end with said tucking and folding members immediately before 45 they are folded down.

3. In a device for closing rectangular bag ends, two pivotally journalled, oppositely disposed, triangularly shaped members for tucking in the ends 50 of two opposite walls of a bag, two pivotally journalled, oppositely disposed members for folding the ends of the two remaining bag walls, driving means for folding down said tucking members towards each other in advance of said folding members and folding down said folding members towards each other upon said tucking members, a member for supporting said bag, and a mechanism operatively connected to said driving means to move said tucking, folding and supporting members relative to each other to embrace the bag end with said tucking and folding members immediately before they are folded down.

4. In a device for closing rectangular bag ends, two pivotally journalled, oppositely disposed members for tucking in the ends of two opposite walls of a bag, two pivotally journalled, oppositely disposed members for folding the ends of the two remaining bag walls, driving means for folding down said tucking members towards each other in advance of said folding members and folding down said folding members towards each other upon said tucking member and upon each other, a member for supporting said bag, and a mechanism operatively connected to said driving means to move said tucking, folding and support-

ing members relative to each other to embrace the bag end with said tucking and folding members immediately before they are folded down.

5. In a device for closing rectangular bag ends, two pivotally journalled, oppositely disposed members for tucking in the ends of two opposite walls of a bag, two pivotally journalled, oppositely disposed members for folding the ends of the two remaining bag walls, driving means for folding down said tucking members towards each other in advance of said folding members and folding down said folding members towards each other upon said tucking members, a member for supporting the bag, an upwardly narrowed, funnel-shaped guide which is positioned below said folding and tucking members and above said supporting member and adapted to give the bag end a reduced cross-section, and a mechanism operatively connected to said driving means to move said guide and said tucking, folding and supporting members relative to each other to embrace the bag end with said guide and said tucking and folding members immediately before said tucking and folding members are folded down.

6. In a device for closing rectangular bag ends, two pivotally journalled, substantially flat and oppositely disposed members for tucking in the ends of two opposite walls of a bag, two pivotally journalled, substantially flat and oppositely disposed members for folding the ends of the two remaining bag walls, driving means for folding down said tucking members towards each other in advance of said folding members and folding down said folding members towards each other upon 35 said tucking members, a member for supporting the bag, an upwardly narrowed, funnel-shaped guide which has a substantially rectangular upper edge and is positioned below said folding and tucking members and above said supporting member and adapted to give the bag end a reduced cross-section, and a mechanism operatively connected to said driving means to move said guide and said tucking, folding and supporting members relative to each other to embrace the bag end 40 with said guide and said tucking and folding members immediately before said tucking and folding members are folded down, said tucking and folding members being pivotally supported at said upper edge of the guide.

7. In a device for closing rectangular bag ends, two pivotally journalled, oppositely disposed tapered members for tucking in the ends of two opposite walls of a bag, two pivotally journalled, oppositely disposed members for folding the ends 55 of the two remaining bag walls, driving means for folding down said tucking members towards each other in advance of said folding members and folding down said folding members towards each other upon said tucking members, a member for supporting said bag, and a mechanism operatively connected to said driving means to move said tucking, folding and supporting members relative to each other to embrace the bag end with said tucking and folding members immediately before they are folded down.

8. In a device for closing rectangular bag ends, two oppositely disposed members for tucking in the ends of two opposite walls of a bag, two oppositely disposed members for folding the ends 70 of the two remaining bag walls, driving means for folding down said tucking members towards each other in advance of said folding members and folding down said folding members towards each other upon said tucking members, a mem-

ber for supporting said bag, and a mechanism operatively connected to said driving means to move said tucking, folding and supporting members relative to each other to embrace the bag end with said tucking and folding members immediately before they are folded down, said tucking and folding members being pivotally movable each about one of four axes that constitute substantially a quadrangle.

10 9. In a device for closing rectangular bag ends, two oppositely disposed members for tucking in the ends of two opposite walls of a bag, two oppositely disposed members for folding the ends of the two remaining bag walls, driving means for folding down said tucking members towards each other in advance of said folding members and folding down said folding members towards each other upon said tucking members, a member for supporting said bag, and a mechanism operatively connected to said driving means to move said tucking, folding and supporting members relative to each other to embrace the bag end with said tucking and folding members immediately before they are folded down, said tucking and folding members being pivotally movable each about one of four axes that constitute substantially a quadrangle having substantially the same area as the cross-section of the bag.

10 10. In a device for closing rectangular bag ends, two pivotally journalled, oppositely disposed pointed members for tucking in the ends of two opposite walls of a bag, two pivotally journalled, oppositely disposed members for folding the ends of the two remaining bag walls, driving means for folding down said tucking members towards each other in advance of said folding members and folding down said folding members towards each other upon said tucking members, a member for supporting said bag, and a mechanism operatively connected to said driving means to move said tucking, folding and supporting members relative to each other to embrace the bag end with said tucking and folding members immediately before they are folded down.

45 11. In a device for closing rectangular bag ends, two pivotally journalled, oppositely disposed members adapted to tuck in the ends of two opposite walls of a bag end and having edges tapering towards one another to form a right angle at the free end of said members, two pivotally journalled, oppositely disposed members for folding the ends of the two remaining bag walls, driving means for folding down said tucking members towards each other in advance of said folding members and folding down said folding members towards each other upon said tucking members, a member for supporting said bag, and a mechanism operatively connected to said driving means to move said tucking, folding and supporting members relative to each other to embrace the bag end with said tucking and folding members immediately before they are folded down.

65 12. In a device for closing rectangular bag ends, two pivotally journalled, oppositely disposed members for tucking in the ends of two opposite walls of a bag, a blade shaped folding member that is pivotally journalled about an axis to fold the end of a third bag wall and has a front edge parallel with its turning axis, a second folding member that is pivotally journalled to fold down the end of the bag end about said front edge, driving means for folding down said tucking members towards each other in advance 70 of said folding members and folding down said

folding members towards each other upon said tucking members, a member for supporting said bag, and a mechanism operatively connected to said driving means to move said tucking, folding and supporting members relative to each other to embrace the bag end with said tucking and folding members immediately before they are folded down.

13. In a device for closing rectangular bag ends, two pivotally journalled, oppositely disposed triangular flaps for tucking in the ends of two opposite walls of a bag, a third flap that is pivotally journalled about an axis to fold the end of a third bag wall and has a front edge parallel with its turning axis, a fourth flap that is pivotally disposed opposite to said folding flap and journalled about an axis parallel with the turning axis of the opposite folding flap to fold down the end of the bag wall about said front edge, driving means for folding down said tucking flaps towards each other in advance of said folding flaps and folding down said third flap upon said tucking flaps and said fourth flap upon said third flap, a member for supporting said bag, and a mechanism operatively connected to said driving means to move said tucking and folding flaps and said supporting member relative to each other to embrace the bag end with said flaps immediately before they are folded down.

14. In a device for closing rectangular bag ends, two pivotally journalled, oppositely disposed members for tucking in the ends of two opposite walls of a bag, a blade shaped folding member that is pivotally journalled about an axis to fold the end of a third bag wall and has a front edge parallel with its turning axis, a second folding member that is pivotally journalled to fold down the end of the bag end about said front edge, driving means for folding down said tucking members towards each other in advance of said folding members and folding down said folding members towards each other upon said tucking members, a member for supporting said bag, and a mechanism operatively connected to said driving means to move said tucking, folding and supporting members relative to each other to embrace the bag end with said tucking and folding members immediately before they are folded down, the distance between the front edge and pivot of said blade shaped folding member being substantially one half of the distance between the turning axes of said folding members.

15. In a device for closing rectangular bag ends, two pivotally journalled, oppositely disposed members for tucking in the ends of two opposite walls of a bag, two pivotally journalled, oppositely disposed members for folding the ends of the two remaining bag walls, driving means for folding down said tucking members towards each other in advance of said folding members and folding down said folding members towards each other upon said tucking members, a member for supporting said bag, and a mechanism operatively connected to said driving means to move said tucking, folding and supporting members relative to each other to embrace the bag end with said tucking and folding members immediately before they are folded down, the distance from the free ends of said tucking members to their pivots being substantially one half of the width of the bag walls to be tucked in by them.
